UNITED STATES PATENT OFFICE.

GEORGE N. BAKER, OF SYRACUSE, NEW YORK.

WINDOW-SCREEN.

No. 907,439.

Specification of Letters Patent.

Patented Dec. 22, 1908.

Application filed December 12, 1906. Serial No. 347,442.

To all whom it may concern:

Be it known that I, GEORGE N. BAKER, of Syracuse, in the county of Onondaga and State of New York, have invented a certain new and useful Window-Screen, of which the following is a specification.

My invention has for its object the production of a window-screen, which is particularly simple in construction and durable in use; and to this end, it consists in the novel combinations and means hereinafter set forth and claimed.

In describing this invention, reference is had to the accompanying drawing, in which like characters designate corresponding parts in all the views.

Figure 1 is a face view of my window-screen. Fig. 2 is an enlarged sectional view, partly broken away, on line A—A, Fig. 1. Figs. 3 and 4 are opposite face views of a corner of my window-screen. Fig. 5 is a plan view of a corner of the frame at an intermediate stage of its process of manufacture. Fig. 6 is a section on line 6—6^a of Fig. 5. Fig. 7 is a view, similar to Fig. 5, of a modified construction of a corner of my window-screen.

This window-screen preferably comprises two overlapping sections adjustable relatively to each other, such sections being duplicates and interchangeable. It is apparent, however, that each of said sections may be employed as a non-adjustable screen.

The frame of each section of the window-screen is composed of preferably two strips of sheet-metal, or other suitable material, folded longitudinally along their middles for forming channels 1 which receive the edges of the central part of the section, as the wire-netting 2. End portions 3, 3 of one of these strips are bent at right angles to the middle portion 4 thereof, each of these portions 3, 3, 4 forming a side of the frame of a

screen-section, and the two sides of this frame formed by the end portions 3, 3 being slidably engaged with the corresponding sides of the frame of the other screen-section. The parts 5 of said strip which are distorted at the corners of the frame by bending the end portions 3, 3 are preferably compressed upon adjacent parts of said corners, the compressed distorted parts on both faces of each of said corners preferably lying on opposite sides of lines, as 6, extending

diagonally through said corners. Such distorted parts may, however, be otherwise compressed upon the underlying parts of the corners, as illustrated in Fig. 7, in which I have shown the distorted part on one face 30 of a corner as of triangular form, and arranged at one side of a line, as 7, passing diagonally through the corner. The other strip of folded sheet-metal of which the frame of a screen-section is composed, preferably forms the remaining or fourth side 8 of said section, and the ends of this strip are preferably provided with hooks 9 bent around, and slidably engaging, the contiguous opposite sides of the frame of the other 70 section of the screen, and serving to hold the screen-sections together.

The outer longitudinal margins of the sides of the frames of the overlapping sections of the window-screen are bent at an angle to the remaining portions of said sides, forming flanges on the opposing surfaces of the screen-sections. As best seen in Fig. 2, the flange 10, on one of the slidably-engaging sides of one of said frames, is located outside 75 of the flange 11 of the corresponding side of the other frame, and the flange 12 on the opposite side of said one of the frames is located inside of the flange 13 of the corresponding side of said other frame. Said flanges 10, 11, 80 12 and 13 form a particularly simple means for guiding the sections of the window-screen in their adjusting movement. The flanges 14 of the sides 8 of the frames of the screen-sections tend to prevent the passage of flies 90 and other insects between the opposing surfaces of said sections. Preferably, the wire-netting 2 extends within the channels 1 of the frames of the screen-sections to near the bottoms of such channels, and consequently, 95 the bending of the outer margins of the sides of these frames for forming marginal flanges on said frames, clamps the netting 2 in position.

As will be obvious to those skilled in the art, a window-screen of the described construction is economically manufactured and is particularly strong and durable in use.

What I claim is:—

1. A frame for a window-screen comprising a strip of metal folded longitudinally for forming a channel, and having angularly-arranged portions for forming a plurality of the sides of the frame, the parts of said strip distorted at a corner of the frame by bending 105 110

the strip being compressed upon adjacent parts of said corner, substantially as and for the purpose set forth.

2. A frame for a window-screen comprising a strip of metal folded longitudinally for forming a channel, and having its end portions arranged at right angles to the middle portion thereof, each of said portions forming a side of the frame, the parts of said strip distorted at corners of the frame by bending the strip being compressed upon adjacent parts of said corners, substantially as and for the purpose specified.

3. A frame composed of a strip of metal folded longitudinally to form a channel and bent upon itself to form two or more of the sides of such frame and having the parts of the metal distorted at the corners by said bending compressed upon the sides at such corners to lie substantially flat thereon.

4. A window screen consisting of a frame composed of a strip of metal folded longitudinally to form a channel and bent upon itself to form two or more of the sides of such frame and having the parts of the metal distorted at the corners by said bending compressed upon the sides at such corners to lie substantially flat thereon, and a screen material secured in such channel.

30 5. A frame for a window-screen comprising a strip of metal folded longitudinally for forming a channel, and having its end portions arranged at right angles to the middle portion thereof, each of said portions forming a side of the frame, the parts of said strip distorted at corners of the frame by bending the strip being compressed upon adjacent parts of said corners, and the outer margins of said sides being bent at an angle to the remaining portions thereof, substantially as and for the purpose set forth.

45 6. A frame for a window-screen comprising a strip of metal folded longitudinally for forming a channel, and having angularly-arranged portions for forming a plurality of the sides of the frame, the parts of said strip distorted at a corner of the frame by bending the strip being compressed upon adjacent parts of said corner, and the compressed distorted part on one face of the corner lying on opposite sides of a line extending diagonally through said corner, substantially as and for the purpose specified.

50 7. A frame for a window-screen comprising a strip of metal folded longitudinally for forming a channel, and having its end portions arranged at right angles to the middle portion thereof, each of said portions forming a side of the frame, the parts of said strip distorted at corners of the frame by bending the strip being compressed upon adjacent parts of said corners, and the compressed distorted part on each face of each of said cor-

ners lying on opposite sides of a line extending diagonally through said corner, and the outer margins of said sides being bent at an angle to the remaining portions thereof, substantially as and for the purpose described.

8. A window-screen comprising two overlapping sections adjustable relatively to each other, the frame of each section being composed of strips of metal folded longitudinally along their middles for forming channels to receive the edges of the wire-netting, such netting extending into the channels to near the bottoms thereof, one strip having its end portions arranged at right angles to the middle portion thereof, each of said portions forming a side of the frame, the parts of said strip distorted at corners of the frame by bending the strip being compressed upon adjacent parts of said corners, and the other strip forming the fourth side of said frame and being provided with hooks at its ends bent around, and slidably engaging, the contiguous sides of the frame of the other section, and the outer longitudinal margins of the sides of each frame being bent at an angle to the remaining portions of said sides, substantially as and for the purpose set forth.

9. A window screen section comprising a piece of screen fabric and an inclosing frame having a plurality of its sides formed of an integral strip of sheet metal, folded longitudinally and having portions bent angularly with respect to each other to form frame bars, which inclose the marginal portions of the screen fabric, the surplus metal at the corners being folded on a line disposed at an angle of 45° to an adjacent frame bar, said fold extending to the exterior corner of the frame, and said surplus metal being flattened, to bring it substantially into the plane of the frame and lock the adjacent frame bars in their relative angular positions, substantially as described.

10. A window-screen, comprising a section of screen material and a metallic frame surrounding the same, a plurality of the sides of said frame being formed of a single uncut piece of metal folded longitudinally upon itself and bent angularly at the corners of the frame, the surplus metal caused by such bending being flattened down into substantially the same plane as other portions of the frame and serving to reinforce the corners thereof, substantially as described.

In testimony whereof, I have hereunto signed my name in the presence of two attesting witnesses, at Syracuse, in the county of Onondaga, in the State of New York, this 26th day of November, 1906.

GEORGE N. BAKER.
